UNITED STATES PATENT OFFICE.

JOSIAH MENTOR GIMSON, JOSIAH GIMSON, ARTHUR JAMES GIMSON, AND SYDNEY ANSELL GIMSON, OF LEICESTER, ENGLAND.

AUTOMATIC CLAMPING PRESSURE MECHANISM.

No. 844,515.

Specification of Letters Patent.

Patented Feb. 19, 1907.

Application filed March 25, 1904. Serial No. 200,070.

To all whom it may concern:

Be it known that we, JOSIAH MENTOR GIMSON, residing at No. 106 New Walk, JOSIAH GIMSON, at Stoneygate House, ARTHUR JAMES GIMSON, at White House, Clarendon Park, and SYDNEY ANSELL GIMSON, at No. 20 Glebe street, all in the county borough of Leicester, England, in the United Kingdom of Great Britain and Ireland, subjects of His Britannic Majesty King Edward the Seventh, have invented new and useful Improvements in Automatic Clamping Pressure Mechanism, to be employed, constructed, and employed for outside or inside heel building or attaching, sole-leveling, stamping, embossing, and other operations of a like kind in the manufacture of boots and shoes.

The object of the said improvements is to provide automatic clamping pressure mechanism that will exert a direct clamping pressure, which is transmitted by plates and blocks upon a plunger, so as to adapt itself and exert the necessary pressure in all the different variations in the height of heels or other articles and in the inequalities of material, and to hold and press them perfectly solid upon or in the heelng or nailing stand for building or attaching them to a boot or shoe.

That this invention may be well understood drawings accompany this specification, in which—

Figure 1 is a partly-sectional elevation of a heel-building machine embodying this invention; and Figs. 2 and 3, Sheet 2, are sections, respectively, through the head of the press, taken on lines *a b* and *c d*; and Fig. 4, Sheet 2, is a sectional elevation of Fig. 1, Sheet 1.

In carrying out this invention relative to the top cross-head *A* spaces are provided for carrying the plunger *B* and the guide-rods *F*, which are attached to both the top and bottom cross-heads in the ordinary manner. The plunger *B* is provided with a removable foot or heel pad *B'* at the bottom thereof. A space is left within the cross-head *A* to hold the gripping-blocks *C*.

It will be well understood that in small heel-attaching machines both for inside or outside nailing only one set of the levers, blocks, and plates are required. One of the faces of the gripping-blocks *C* is hollowed out and so shaped as to fit half round the plunger to grip it, (see dotted line, Fig. 1,) and in the opposite face of each of the said blocks is a re-

cess large enough to admit of one of the plates *D* to be placed therein, the other end of such plates fitting in recesses in the periphery of the levers *E*, which are pivoted to the upper cross-head *A* in spaces contiguous to the gripping-blocks *C*, said levers *E* being parallel to the tie-rods *F*, which rods are fitted to the top cross-head *A* and pass through the pillars or carriers *F'*, and the bottoms thereof are secured to the lower cross-head, as shown in Figs. 1 and 4. The lower free ends of the levers *E* carry rollers *G*, which engage with the horizontally-disposed eccentric cams *H* and *I*, loosely-fitted on the pillars or rod-carriers *F'*. Said cams after being turned to the right position are made fast by the set-screws *h* and *i*, and so regulate the pressure of the lower ends of the levers *E*. To adjust the top of the adjustably-fulcrumed levers *E* with the plates *D*, the pins *J* (seen in Figs. 2 and 3) are employed, the central portion of which is eccentric and the remaining parts concentric, and when required to be turned a key with two pins to fit in the holes *j* is employed when desired.

The before-mentioned contrivances are shown as applied to a movable top cross-head; but they may also be applied to a fixed top cross-head—that is to say, to a machine in which the nail stand or die is caused to rise upward to a stationary head or opposite to the machine shown in the drawings. In either case upon the first part of the movement the roller ends of the levers *E* will be in contact with the face of one of the eccentric cams, and the plates *D* will be held with the desired pressure against the gripping-blocks *C*, and the plunger *B* will be either raised or lowered. After the plunger has been moved down with its foot or pad *B'* nearly touching or just within reach of the heel to be operated upon the roller ends *G* of the levers *E* will simultaneously leave the face of the cams *H*, and the foot of the plunger *B'* falls onto the heel and remains there until the machine makes a further movement, when the rollers *G* of the levers *E* engage the cams *I* and when the lower ends of the levers *E* will be pushed farther out, and so alter the position of the plates *D* and press against the gripping-blocks *C* with such a force that the plunger *B* is held from further movement relative to the cross-head *A*, the foot or pad of the plunger bearing upon the heel to make it solid

and hold it against the opposite action of nail-driving. After the rollers G have left the lower cams I and before they engage the upper cams H the gripping-blocks C release the plunger B, when it immediately adapts itself to the height of the heel. The adjustably-fulcrumed levers E exert a direct action transmitted by the plates D and gripping-blocks C upon the said plunger.

- 10 It is obvious that the aforesaid contrivances are not confined to the machine as illustrated in the drawings, for they can be fitted to others in which the plunger can be made to adapt itself to the height or thickness of the article or material to be operated upon.

15 We would have it understood that no claim is made to the cams which operate the lower cross-head, and therefore no reference letters are employed to that portion.

20 We claim—

In a machine of the character described the

combination with upper and lower cross-heads, of rods connecting said cross-heads, springs tending normally to elevate said rods, 25 hollow pillars in which said rods are guided, cams mounted on said pillars, a plunger loosely mounted in said upper cross-head, gripping-blocks partly surrounding said plunger, levers adjustably fulcrumed in said upper 30 cross-head, rollers carried by said levers and engaging said cams, and transmitting-plates connecting said levers and gripping-blocks, substantially as and for the purpose set forth.

In testimony whereof we have signed our 35 names to this specification in the presence of two subscribing witnesses.
